W. H. GOWDRIDGE

AUGER BIT

Filed Dec. 3, 1923

FIG. 1.

FIG. 2.

FIG. 3.

FIG. 4.

W. H. GOWDRIDGE INVENTOR

BY *Victor J. Evans*

ATTORNEY

UNITED STATES PATENT OFFICE.

WILLIAM HENRY GOWDRIDGE, OF ROSSITER, PENNSYLVANIA.

AUGER BIT.

Application filed December 3, 1923. Serial No. 678,306.

To all whom it may concern:

Be it known that I, WILLIAM H. GOWDRIDGE, a citizen of the United States, residing at Rossiter, in the county of Indiana and State of Pennsylvania, have invented new and useful Improvements in Auger Bits, of which the following is a specification.

This invention relates to auger bits, and more particularly to an auger bit specially adapted for use in coal mining and similar operations.

One of the main objects of the invention is to provide an auger bit of simple construction and operation which can be quickly and easily resharpened thus effecting a material saving in time. A further object is to provide a bit having means serving as guide means for resharpening the bit so as to obtain accuracy in sharpening thereof. Further objects will appear from the detail description.

In the drawings:—

Figure 1 is a side view of the auger as used;

Figure 2 is an enlarged side view, partly broken away;

Figure 3 is a plan of the tip before twisting of the same;

Figure 4 is a section taken substantially on line 4—4 of Fig. 3.

The auger A is of well known construction and includes a bit or "pod" a from which extends a shank b provided with a crank c and a pressure-applying member d. In the present type of auger commonly used, when the points or prongs of the bit or "pod" a become dull, or if the prongs break, it is necessary to carry the auger to the blacksmith shop to have it resharpened or repaired. This means a considerable loss of time to the miner with a consequent loss in production. To avoid this objection I provide a terminal or tip member 1 to the outer end of which is secured a screw-stud 2 which threads into a corresponding socket 3 provided in the end of "pod" a remote from shank b. Member 1 is initially formed as a flat blank provided with slots 1^a, 1^b and 1^c, the latter slot extending from the prong or

working end of the blank. This provides, in effect, two parallel plates or strips 4 connected by webs 5, the outer ends of these strips being integrally connected together. This member is then twisted into substantially spiral form so as to produce a tip member which can be readily attached to the "pod" a. When member 1 is twisted the slots 1^a, 1^b and 1^c provide openings through which slivers of coal removed by the prongs 4^b can readily pass so as to prevent clogging or jamming of the tip member, the slack being fed out of the hole bored by the "pod". In the event that the prongs 4^b become dull or are broken the tip may be readily removed or detached from "pod" a and replaced by a new tip. For this purpose the miner may carry several tips in his pocket. In addition to facilitating twisting of the member 1 and providing means for escape- 70 ment therethrough of slivers of coal, the slots 1^a, 1^b and 1^c serve as guides in filing or sharpening the prongs 4^b. Preferably, though not necessarily, I provide a set screw 6 which is threaded into the thickened portion of "pod" a in which the socket 3 is provided, this set screw being adapted for engagement with shank 2 so as to lock the "pod" and the tip together.

While I have illustrated and described my 80 auger as being used for boring coal it can also be used for boring rock and other materials. As the tip can be readily applied and replaced it will be apparent that my invention effects a material saving in time 85 which is an important consideration in mining operations.

What I claim is:—

1. In an auger, a bit portion, and a tip member detachably secured to the end of 90 the bit portion, said tip member being provided with openings between the convolutions thereof.

2. As a new article of manufacture, an 95 auger tip member adapted for securement to the bit portion of an auger and provided with central openings disposed coaxially with said member.

In testimony whereof I affix my signature.
WILLIAM HENRY GOWDRIDGE.
